O. L. HANKINS

AUTOMATIC SELECTIVE VALVE

Filed April 24, 1925

UNITED STATES PATENT OFFICE.

OSCAR L. HANKINS, OF TOPEKA, KANSAS.

AUTOMATIC SELECTIVE VALVE.

Application filed April 24, 1925. Serial No. 25,661.

To all whom it may concern:

Be it known that I, OSCAR L. HANKINS, a citizen of the United States of America, residing at Topeka, in the county of Shawnee and State of Kansas, have invented certain new and useful Improvements in Automatic Selective Valves, of which the following is a specification, reference being had to the drawings forming a part hereof.

10 My invention relates to an automatic valve device designed for use in rural or suburban houses (for example) where two sources of two different kinds of water exist nearby and it is required to have either kind 15 of water on tap at each lavatory, sink, or bathtub.

The object of the invention is to provide means for such dual supply without the necessity of persons going to the basement 20 to open or close a valve or valves in order to connect the desired kind of water to a faucet.

This object could be attained without such extra manipulation if the supply pipes 25 were led to two independent pressure reservoirs, if two force-pumps were also provided for maintaining pressure in the respective reservoirs. My invention provides the desired service in connection with a single pump and a single pressure-tank, whereby a substantial saving of money is 30 effected.

I use the term pressure-tank above in a generic sense, for the reason that it will not 35 be in all cases necessary to employ a tank in connection with the feed pump. In houses where both kinds of water are likely to be used every day, or say once or twice a week, the air chamber of the pump will perform 40 the function of the air cushion in a tank, and a more immediate supply of the proper kind of water through a faucet will occur than with a tank.

A preferred embodiment of the invention 45 is shown in the accompanying drawing, which is partly diagrammatic, and in which—

Fig. 1 is a plan view of the device showing certain parts in horizontal section;

50 Fig. 2 is a vertical sectional view on line II—II of Fig. 1, omitting two of the check-valves;

Fig. 3 is a detail face view of one of the valve-actuating pistons.

Fig. 4 is a diagram showing a power 55 pump, a pressure-tank and their connections in part.

On Fig. 1, the letters B and C denote respectively, pipes leading from two separate sources of different kinds of water, as, for example, a well and a cistern. Said pipes are respectively connected by nipples 5 5' to a pair of check-valves 6 6'. These check-valves are connected respectively, by nipples 7 7', with a pair of check-valve bodies 8 8', 65 which are mounted on opposite ends of a rectangular cast metal box, 9, by means of nipples 10 10' as shown.

Said box has a removable side or top, 9'. Check-valves 6 6' close outwardly—i. e., 70 opposite the direction of flow in pipes B C, as indicated by arrows adjacent said valves which indicate the direction of opening.

The arrangement of valves 6 6' and 8 8' is the same at both ends of the chambered 75 body 9.

The check-valves in valve bodies 8 8' are as shown of the hinged valve type, as shown in Fig. 2, wherein 12 12' are the valves proper and 13 13' their hinges. 80

The operation of these valves as to their opening, is controlled by push-rod 14, longitudinally slideable in cap-bearings 15 15'.

Rod 14 as shown has an integral lateral arm 16 having a pin-and-slot connection 17 85 18 with a rock-arm 19, pivoted in the box at 20 and extending horizontally in close proximity to rod-arm 16 and beyond same, in order to make operative engagement with a piston rod 21. As shown, this connection 90 is constructed as an integral crosshead 22 in or at the centre of the rod, with a straight slot 23 therein, and a pin 24, rigidly carried by rock-arm 19, taking into the slot. Desirably, the portion of arm 19 bearing the 95 pin 24 is bifurcated to straddle the cross-head.

The piston rod 21 extends symmetrically in opposite directions from its central cross-head, and will be further described as to its 100 right-hand end, it being understood that the construction to be described is duplicated at the opposite end of the device.

The box 9 is bored and threaded to re-

ceive a stuffing-box member as 25, having a counterbore in which a ring packing 26 is held by a screw gland 27. Threaded upon member 25 is a three-way T union 28, to the 5 lateral of which is connected a pipe H. A short cylinder 29 of brass tubing, or of iron pipe, is screwed into the outer end of the union, and is connected to a pipe E by a coupling 30.

10 The right half of rod 21 extends through union 28 into the cylinder 29 and past the centre thereof even when in neutral position; in other words, the piston or disc 32, fixed on the end of rod 21, will stand about 15 midway of its cylinder when at neutral position. As most clearly shown by Fig. 3, the piston is either notched in its periphery, as at 33, or is provided with holes for ports if its periphery be circular. In practice, this 20 piston receives the impact of suddenly admitted liquid under pressure, through pipe H, yet will permit a sufficient flow of liquid outwardly to pipe E.

The above description applies equally to 25 the piston 30', shown in dotted lines at the left of Fig. 1, and to the pipes D, G.

The valve push-rod 14 is made of such length that when either end of it is in contact with a closed valve, 12 or 12', its opposite end holds the opposite valve fully open.

Pipes D and E lead to a pair of faucets (not shown) of the usual kind and which may belong to any lavatory, sink or bath tub 35 in the house.

Referring now to Fig. 4:

N denotes an electrically driven pump of any known make, provided as is usual with an automatic starting and stopping device 40 controlled by pressure. M denotes a pressure-tank which is fed from the pump at 42. The pump has another pressure-outlet, 43, which in practice is connected to pipe G, Fig. 1. The tank outlet, 44, is connected to the soft-water end of the device—that is, to 45 pipe H. The pump intake, 35, is connected in practice to pipe J.

The device shown in Fig. 1 is installed upon or adjacent to the pump, and serves 50 for all the faucets in the house, as branch pipes are led from pipes D and E to each pair of taps in the building.

Supposing that each pair of faucets is to 55 deliver cold "hard" and cold "soft" water, the operation will be as follows for drawing soft water: I open the faucet connected with pipe E; this allows water to rush into cylinder 29 through pipe H; the pressure on piston 30 forces the piston, with rod 21, to 60 the right until collar 37 strikes the wall of the chamber; this movement rocks the rock-arm 19 in the same direction. This is transmitted to arm 16 and push-rod 14, which impinges on cheek-valve 12' and opens it. 65 Water is thus admitted from supply pipe

C to the suction pipe J of the pump, and the faucet which is open receives a constant flow of water through pipes C, H and piston 30 in this way.

When drinking (spring) water is desired, 70 the left-hand faucet is opened. Piston 30 moves outward, shifting the push-rod to the left, thus opening valve 12. Hard water now flows from pipe B through chamber K, pipe J, pump, pipe G, piston 30' and pipe 75 D to the faucet. The opening of valve 13 was almost simultaneous with the closing of the other valve 12' which shuts off the soft water line.

As before stated, I prefer that the spring 80 water be taken directly from pump to the faucets, without any pressure-tank being interposed, though I do prefer to employ a pressure-tank in the soft-water side of the system.

The piping layout itself is no part of my invention, and full illustration thereof has been deemed superfluous. In this connection it should be stated that any competent plumber can install pipes and a hot-water 90 heater in connection with my device in such a way that a third faucet for hot water may be added to each lavatory, and hot water from the cistern side of the plant may be had by opening any hot water faucet, without 95 any alteration whatever of the automatic valve device from the construction here shown.

Having thus described my invention, what 100 I claim as new and desire to secure by Letters Patent is:

1. In a fluid pressure actuated means, 105 said means comprising a pair of cylinders mounted on the chamber, each cylinder having an outlet to a faucet and an inlet from a source of pressure, pistons with ports, in the respective cylinders, a reciprocal rod connecting the pistons and passing through the chamber, and a mechanical movement connected with said rod. 110

2. A box, opposed tubes connected with opposite ends of the box, a pivoted valve in each tube, and a reciprocable push-rod so arranged as to open either pivoted valve 115 while permitting the other to close.

3. In combination with claim 2, a reciprocal rod passing through the box, opposed pistons on said rod, cylinders containing the pistons and mounted on opposite sides of the box, and means for actuating the 120 push-rod from the piston-rod, each of the cylinders being provided with an intake at one side of the piston and an outlet at the other side of the piston.

4. In combination, a box containing a 125 water-chamber, and having a bore in one wall, a stuffingbox threaded in the bore, a three-way union threaded to the stuffingbox with its main axis aligned with that of the stuffingbox, a tube threaded to said union 130

on the main axis, a ported piston in the tube, and a piston rod secured to the piston and passing through the stuffingbox into the water chamber aforesaid.

5. A box, a rock-arm pivoted therein, a pair of reciprocable rods passing through the box in parallel relation, suitable bearings for one of the rods, packed bearings for

the other rod, a connection between the end of the rock-arm and one rod, and a similar 10 connection between a different point on the rock-arm and the other rod.

In testimony whereof, I have this day affixed my signature.

OSCAR L. HANKINS.
